O. E. McCUMBER,
WEIGHING ATTACHMENT FOR ICE BOXES,
APPLICATION FILED DEG. 26, 1913.

1,094,581.

Patented Apr. 28, 1914.

UNITED STATES PATENT OFFICE.

ORINDA ELIZABETH McCUMBER, OF OMAHA, NEBRASKA.

WEIGHING ATTACHMENT FOR ICE-BOXES.

1,094,581.

Specification of Letters Patent. Patented Apr. 28, 1914.

Application filed December 26, 1913. Serial No. 808,638.

To all whom it may concern:

Be it known that I, ORINDA ELIZABETH McCUMBER, a citizen of the United States, residing at Omaha, in the county of Douglas and State of Nebraska, have invented certain new and useful Improvements in Weighing Attachments for Ice-Boxes, of which the following is a specification.

This invention relates to weighing attachments for ice boxes, and has for its object, broadly, to provide devices for weighing ice after it has been placed in the box, the means for this purpose to consist of few and simple parts, so that they may be economically constructed.

The construction shows a receptacle for containing ice which conforms, in cross-section, to the shape of the box, and so arranged that it may be conveniently removed therefrom when desired, and when placed therein will form air-passageways between its sides and the walls of the box, devices being employed by means of which the weight of the ice within the receptacle may be ascertained at any time.

The invention consists of the novel construction, combination and arrangement of parts as described herein and claimed, and as illustrated in the drawing, wherein,—

Figure 1 is a view, in longitudinal section, of an ice box provided with weighing attachments, the section being substantially through the middle of the box, as on line 1 1 of Fig. 2. Fig. 2 is a transverse section taken through the box below the ice receptacle to illustrate an arrangement of levers and their supports, a part of the ice receptacle being added. Fig. 3 is a sectional view showing a part of the inner face of one of the side walls of the box, to illustrate means for automatically terminating the tension of the spring, as a section on line 3 3 of Fig. 1. Fig. 4 is a side view of an index for the scales. Fig. 5 is a bottom plan view, on a reduced scale, of the ice receptacle.

Referring now to the drawing for a more particular description, numerals 6 and 7 respectively indicate the side walls of an ice box, its front and back being respectively indicated at 8 and 9. The ice box thus shown is rectangular in cross-section, and its lid 10 is mounted upon the back, in the usual manner, by means of hinges 11.

At 12, disposed transversely midway between the front and back of the box, is a main lever, one of its ends being fulcrumed

at 13 in the side wall 6. An elongated aperture 14 is formed in the side wall 7, through which the lever may project.

At 15 is indicated a wheel which may be provided with a shaft 16 having bearings in bracket 17 secured upon wall 7, above aperture 14; and the periphery of wheel 15 may be provided with an index a. Mounted upon shaft 16 is a crank 18, and at 19 is indicated a connecting rod having its respective ends mounted upon this crank and lever 12. The parts may be so proportioned that member 15 may be rotated substantially 180 degrees by an upward or downward movement of lever 12.

At 20 is indicated a spring, one of its ends being mounted upon bracket 21 secured upon wall 7, its opposite end being mounted upon rod 19; and it is obvious that a downward swinging movement of lever 12, working in aperture 14, will be subject to the resistance of the spring to cause a rotatable movement of member 15; and as thus described, it may be said that lever 12 is resiliently mounted.

At 22 is indicated a receptacle having downwardly projecting lugs 23 secured upon its bottom. At the junction of the side walls with the front and back of the box are secured brackets 24. At 25 are indicated a plurality of secondary levers, each having one of its ends fulcrumed in a bracket 24, its opposite end being disposed upon the disk 26, said disk having a projection b extending downwardly for a pivotal mounting in the enlarged part c of lever 12. Brackets 24 are normally disposed in a horizontal plane. Levers 25 are of uniform length and may be arranged to engage disk 26 at substantially uniform distances from projection b, and preferably, disk 26 is disposed substantially at equal distances from the sides, midway between the front and back of the box. Levers 25 are provided, at uniform distances from their outer ends, with depressions or grooves d; lugs 23 are disposed uniformly upon the bottom of receptacle 22, each being equi-distant from a corner of said receptacle; and when the receptacle is placed on levers 25 each lug 23 will engage in a depression d while disposed at right angles with the lever upon which it is supported.

As thus described the parts provide convenient means for weighing ice. At the time ice is purchased it may be placed in receptacle 22, as shown in Fig. 1, and its

weight may be ascertained by reference to the index. The bottom of the receptacle is provided with a drain pipe 27, and water from melted ice may be discharged within 5 pipe 28, these parts, however, being so disposed that pipe 27 will not make contact with pipe 28 to interfere with the operation of weighing.

At 29 is indicated an angular flange disposed at the lower part and mounted upon the upright walls of receptacle 22, to provide a container or drain for the condensed moisture which may form on the outer surface of said walls, and the water from this 15 source may pass into the receptacle through port *e*.

It will be noted that the receptacle 22 is normally disposed adjacent to the upright walls of the box, and may be conveniently 20 removed and replaced, this being of advantage for sanitary reasons, and on account of the construction as described, a passageway *h* is provided which extends entirely around said receptacle to permit a free circulation 25 of air. Also on account of the provision of disk 26 and its mounting, and the mounting of the secondary levers 25 thereon, the receptacle 22 is supported to advantage. It may have a slight vertical movement during 30 the operation of weighing the ice, but it may not have a sidewise swinging movement at any time.

Since attachments for weighing ice, as described, would be of no practical advantage 35 unless the weight thereof could be accurately determined, and since a continued strain of the spring would tend to injure or weaken it, means are provided for preventing any strain or tension of the spring while 40 the lid is closed. This may consist, in part, of a cam 30 which may be mounted upon wall 7 by means of the pivot-pin 31 which is disposed below lever 12 adjacent to aperture 14. Mounted upon wall 7 is a rock 45 lever 32. Upon one of the arms of the rock lever is pivotally mounted one end of a link 33, the opposite end of this link being pivotally mounted upon the cam. Upon the other arm of the rock lever is pivotally mounted 50 one end of the link 34, its opposite end being pivotally mounted upon bracket 35, said bracket being mounted upon the lid 10 of the ice box. The parts are so arranged that when the lid is raised the cam may have a 55 rotatable movement, substantially, of 180 degrees so that it will not engage lever 12, and the weight of receptacle 22 and its contents will cause said lever to swing downwardly in aperture 14 subject to the resistance of spring 20, at which time said weight 60 may be determined by the index *a*. A downward swinging movement of the lid, however, will cause reverse movements of the arms of the rock lever, to that last described, and the rotatable movement of the cam will

cause its periphery to engage lever 12 and will cause the lever to swing upwardly. The upward swinging movement of said lever will cause rod 19 to move upwardly to terminate the tension of the spring, and 70 lever 12 will be in engagement with the cam at all times except when the lid is completely raised. Means are provided tending to prevent the lid from closing and to maintain it in an upright position until manually 75 closed. For this purpose the pivotal mounting for the rock lever consists of the thumb screw 36 in engagement with said rock lever and with block 37, as best shown in Fig. 1. By an adjustment of the thumb screw a 80 pressure of said screw against the rock lever may be made sufficient in degree to prevent the lid from swinging downward from accidental causes, but the lid may be closed by manually grasping it and swinging it downwardly against the force of said pressure. 85

Means are provided for causing a closure of the aperture 14 of wall 7 within which lever 12 moves, to thereby prevent an undue melting of ice. This aperture must be of 90 ample size to permit the movements of link 12 without binding or undue friction and a closure of said aperture is therefore necessary. By reference to Fig. 3 it will be seen that the operation of the rock lever 32 will 95 cause the cam to be disposed in its lowermost position when the lid 10 is raised, and the operation of these parts is such that when the lid is swung downward or closed, the cam will be elevated to the position shown 100 by the dotted, circular line; and by these means, which operate automatically, a closure will be made of substantially all of the area of the aperture, except the space occupied by the lever, and this closure of the 105 aperture will continue while the lid 10 remains closed.

While I have described construction in detail, it has been for the purpose of clearly explaining one embodiment of the invention, 110 and it will be understood that I may make certain changes in form, size, proportion and minor details, within the scope of the appended claims.

What I claim and desire to secure by Letters Patent is,—

1. In weighing attachments for an ice box, the combination of a main lever disposed transversely of and fulcrumed in the box, a spring supported by the box and connected 120 with said main lever; a disk provided with a projection and supported by the main lever; a plurality of secondary levers fulcrumed in the box and supported by the disk, a receptacle mounted on the secondary levers for moving said main lever and for causing a tension of the spring; an index adapted to be actuated by a movement of the main lever; a cam mounted upon the box, and means to move the cam into engagement 125

130

- with the main lever for relieving the tension of the spring.
2. In combination with an ice box having a movable lid, a main lever disposed transversely of and fulcrumed in the box, a spring supported by the box and connected with said main lever; a disk provided with a projection and supported by the main lever; a plurality of secondary levers fulcrumed in the box and supported by the disk; a receptacle mounted on the secondary levers for moving said main lever and for causing a tension of the spring; an index adapted to be actuated by a movement of the main lever; a cam mounted on the box; and an arrangement of links connected with the cam and said lid for moving the cam into engagement with the main lever by one of the movements of the lid for terminating the tension of the spring.
3. In combination with an ice box having an apertured wall and a movable lid, a main lever traversing the aperture of said wall and fulcrumed in the box, a spring supported by the box and connected with said main lever; a receptacle supported by said main lever for causing a tension of the

spring; an index adapted to be actuated by a movement of the main lever; a cam mounted on the box; an arrangement of links connected with the cam and said lid for causing a rotatable movement of the cam by a movement of the lid, the operation being that said movement of the cam will cause a closure of a part of said aperture and will cause a movement of the main lever for terminating the tension of said spring.

4. In combination with an ice box having an apertured wall and a movable lid, a lever disposed in said aperture and fulcrumed in the box, a spring supported by the box and connected with the lever, a receptacle supported by the lever for causing a tension of the spring, and a cam adapted to be actuated by a movement of the lid for making a closure of a part of the aperture of said wall and for terminating the tension of the spring.

In testimony whereof I have affixed my signature in presence of two witnesses.

ORINDA ELIZABETH McCUMBER.
